UNITED STATES PATENT OFFICE.

LOUIS V. ARONSON, OF NEWARK, NEW JERSEY.

DESIGN FOR A CLOCK-CASE.

SPECIFICATION forming part of Design No. 35,797, dated March 11, 1902.

Application filed February 11, 1902. Serial No. 93,631. Term of patent 3½ years.

To all whom it may concern:

Be it known that I, LOUIS V. ARONSON, a citizen of the United States, residing at Newark, in the county of Essex and State of New Jersey, have invented and produced a new and original Design for a Clock-Case, of which the following is a specification, reference being had to the accompanying drawings, forming a part thereof.

10 Figure 1 is a front elevation of a clock-case embodying my new design. Fig. 2 is a side elevation of the same.

As shown in the accompanying drawings, the leading or material features of my design are the pedestal with fancy capital, the figure of the cupid with arms upraised, and the clock-socket encircled with scrolls and having an upwardly-projecting scroll extended to the arm of the cupid.

20 This design comprises a base *a*, supporting a pedestal or truncated column *b*, having a fancy scroll capital with naked figure of cupid *c* standing thereon, the right arm of the cupid being extended and the socket *d* for the clock disposed at one side of the cupid's lower limbs

and below the right arm, the casing of the socket being encircled with scrolls, one of which touches the knee of the cupid, and also having an upwardly-projecting scroll in contact with the cupid's arm. The left arm of 30 the cupid is upraised and feathery wings project from the shoulder-blades.

The whole design is in the style of Louis the XIV in the eighteenth century, the pedestal having scrolls and ornamental accessories in 35 accordance with that style and some delicate drapery extending from the bottom of the clock-socket.

Having thus described my invention, what I claim is—

The design for a clock-case as herein shown and described.

Signed at Newark, in the county of Essex and State of New Jersey, this 3d day of February, 1902.

LOUIS V. ARONSON.
